Des. 232,451

Patented Aug. 20, 1974

232,451

PLAYGROUND CLIMBER REPRESENTING A FLOWER

Robert S. Wormser, Hillsdale, Mich., assignor to Game Time, Inc., Litchfield, Mich.

Filed Feb. 12, 1973, Ser. No. 331,977

Term of patent 14 years

Int. Cl. D21—02

U.S. Cl. D34—5 H

FIG. 1

FIG. 2

FIG. 5

FIG. 4

FIG. 3

FIG. 1 is a perspective view as taken from the front and left of a playground climber illustrating the design of my invention.

FIG. 2 is a rear, elevational view,

FIG. 3 is an elevational view as taken from the left of my new design,

FIG. 4 is an elevational view as taken from the right side of FIG. 1, and

FIG. 5 is a top plan view.

I claim:

The ornamental design for a playground climber representing a flower, substantially as shown and described.
